FUEL SUPPLY SYSTEM

Ferdinando Cario Reggio, Buffalo, N. Y.

Application October 21, 1938, Serial No. 236,249

22 Claims. (Cl. 123—139)

This invention relates to a fuel supply system for an internal combustion engine and in particular to mechanisms for supplying liquid fuel under pressure and in measured quantity to an internal combustion engine. The invention is particularly applicable for the control of the quantity of fuel supplied and for the control of the timing adjustment of the intermittent fuel discharge.

One object of the invention is a fuel pump in which the quantity of fuel supplied at high pressure by the pump is controlled by adjusting the variable and relatively low pressure at which fuel is delivered to said pump.

Another object is to provide a hydraulically controlled engine fuel injection system.

A further object of the invention is to provide means for the accurate determination of the either fixed or controllable timing of the intermittent fuel supply.

A still further object is to provide means for hydraulically controlling the fuel delivery of the engine injection pump and using the hydraulic medium to cool said pump.

Another object of the invention is a fuel pump vented or scavenged with a quantity of fuel increasing or decreasing with an increase or decrease respectively of the quantity of fuel supplied by the pump, and in which a cushion chamber is provided to reduce the periodical pressure surges in the low pressure fuel delivered to the pump.

Another object is to combine an injector valve and spray nozzle with a fuel pump in one unit assembly, vented so it can operate at any angle with the vertical line as it may be required in aircraft engines of the radial type.

Another object is to provide speed regulating or governing means including fluid pressure actuated engine fuel control means and a valve for controlling the latter, wherein the valve is actuated by the centrifugal force transmitted thereto from a flyball mechanism and by a variable fluid pressure load exerted thereon.

A further object of the invention is to provide in the fuel pump unit hydraulically operated means for controlling the timing of the fuel discharge.

Still another object of the invention is to provide a fuel pump of the type described in the first object mentioned above, transfer means for delivering fuel or other suitable fluid such for example as lubricating oil at variable and relatively low pressure to the pump, and control means operable manually or by any suitable de-

vice such as a governor whereby the pressure of the fluid delivered to the pump and in turn the quantity of fuel supplied by the pump can be controlled.

5 The above and other objects of the invention will be apparent as the description proceeds; and while I have illustrated and described the preferred embodiments of the invention as they now appear to me, it will be understood that such changes may be made as fall within the scope of the appended claims. In the following description and in the claims various details will be identified by specific names for convenience, but they are intended to be as generic in the application as the art will permit.

The accompanying drawings show an example of application of the invention to a plunger pump comprising, enclosed in one unit assembly, a spring loaded spray nozzle valve. Delivery of 10 fuel through the loaded valve occurs during the middle portion only of the discharge stroke of the plunger, the beginning and the ending of the plunger stroke being made ineffective by the opening of a port controlled by the pump plunger. The pump plunger is provided with at least one helical control edge whereby the quantity of fuel delivered may be varied by a turning adjustment of the plunger, effected through a rack 15 engaging a pinion loosely splined on the plunger and wherein the plunger can reciprocate. The rack is connected with the movable wall of a bellows included in the pump unit and urged in opposite directions by a spring and by a suitable fluid which in the example shown is the fuel 20 delivered to the pump through the low pressure fuel line by fuel transfer means whose output is in excess of the pump requirements. The excess fuel flows continuously through a spring 25 loaded relief and pressure regulating valve connected with the low pressure line.

30 Pressure variations in this line will expand or contract the bellows and thereby rotate the plunger. Manually operable control means, or automatic means such as governors, or both, are 35 provided to control the load of the relief valve spring whereby the pressure of the fuel in the low pressure line and in turn the quantity of fuel supplied by the pump can be controlled.

40 The usual linkage operatively connecting the 45 governor with the pump, and in multicylinder engines interconnecting the pumps, to control the fuel supply, can therefore be eliminated. It will further be appreciated that, since the governor has not to overcome the friction resistance 50 opposed by the pumps and by the control linkage,

but it has only to operate the relief valve, its energy and in turn its dimensions can be comparatively very small.

It is further to be noted that should, while a multicylinder engine is operating, a pump plunger seize in its cylinder, the plunger would remain inoperative at the end of its discharge stroke, its spring being unable to lift the plunger, while the other pumps would keep on supplying fuel to the engine. In conventional fuel supply systems in which the means for turning the pump plungers are positively interconnected, the seized plunger might prevent the control means from adjusting the delivery of the remaining pumps and thereby put the engine out of control. Obviously, such hazard is eliminated by the hydraulically operated means forming part of this invention, with which the seized pump cannot prevent the remaining pumps from being controlled by the adjustable pressure of the fuel in the low pressure line.

Resilient storing means, shown in the drawings as air cushion chambers, are provided to reduce the periodic pressure surges caused in the low pressure line when the port leading to the pumping chamber is uncovered and covered by the plunger. In those of the pump units designed for discharging at any angle with the vertical line chambers for air cushioning are located in different points within the unit housing and surround the port, and suitable venting means together with a return conduit are provided to eliminate from the pump air or gas in excess of the amount required to secure cushioning in order to reduce the danger of air or gas bubbles being admitted through the port to the plunger pumping space. Such venting means consist of conveniently located apertures of small area connecting the low pressure line with the return conduit through which such bubbles together with a certain amount of fuel are led back to the fuel tank or to the low pressure fuel line. The volume flowing through an orifice under a certain difference of pressure being for the air or a gas several times greater than for a liquid, the areas of the apertures can be made such that under the existing difference of pressure between low pressure line and return conduit all air or gas in excess of that required for cushioning can be eliminated while only a relatively small volume of liquid fuel escapes through the vents.

Vents can also be suitably arranged in the plunger pumping chamber, such vents consisting of small apertures connected with the return conduit through a duct having a port controlled by a control edge formed on the pump plunger whereby flow through the vents is established during the "dwell" period provided by the "dwell" portion of the cam between the end of the plunger suction stroke and the beginning of its discharge stroke. In that preferred embodiment of the invention which is illustrated in the drawings, the angles of the helical edges of the plunger are such that, at an increase of pressure in the low pressure system or line correspond an increase of fuel delivery, so that also the flow through the vents is increased or decreased as the fuel supplied by the pump is increased or decreased respectively, whereby the possibility of eliminating all air or gas bubbles from the pump unit with the minimum flow of fuel is increased. A further advantage of said preferred embodiment is that, if the fuel pressure in the low pressure system should accidentally drop, as it might be due for

example to a fuel leakage, or rupture of fuel line, or partial or total interruption of the fuel transfer pump discharge caused for instance by vapor lock, clogged fuel filter or empty fuel tank, the engine fuel supply and thereby the engine speed immediately decrease. This is not true of hydraulically controlled fuel injection pumps which have been proposed, in which an accidental decrease of pressure of the actuating fuel or other fluid determines an increase of fuel supply and thereby an increase of engine speed which may attain unsafe proportions.

By employing a well known type of hydraulic valve lifter as shown in Fig. 7, or other suitable hydraulic or mechanical slack adjusting device, in combination with a suitable fuel pump unit, the timing adjustment of the pump or of the nozzle discharge may be controlled, in a manner to be later described.

In the drawings:

Figure 1 is a sectional elevation of a combined fuel pump and injection nozzle mounted vertically in the cylinder head of an internal combustion engine to inject downwardly.

Figure 2 is a section on line 2-2 of Fig. 1 showing the hydraulically operated means for angular adjustment of the plunger.

Figure 3 shows a fuel pump and nozzle unit having means for venting the low pressure pump system independently of the direction relative to the vertical line in which direction the pump discharges.

Figure 4 is a section on line 4-4 of Fig. 3.

Figure 5 shows the means for venting the plunger pumping chamber of a pump-nozzle unit discharging downwardly.

Figure 6 shows a fuel pump and nozzle unit as in Fig. 3 including means for venting the plunger pumping chamber.

Figure 7 shows partly in section and partly in elevation a pump unit, means for operating the pump and means for hydraulically adjusting the timing of the pump discharge.

Figure 8 schematically shows a pump, a transfer pump and means for manually controlling the quantity of fuel supplied by the pump and the timing of the pump delivery.

Figure 9 shows a scheme similar to Fig. 8 including automatically operated control means.

Figure 10 schematically shows two pump units connected with the means for controlling their fuel supply and the timing of their periodic delivery.

In the example of application of the invention which is illustrated in the drawings the fluid medium employed for the hydraulic control of the fuel delivery of the injection pump is the fuel itself.

In all the drawings the pump plunger is shown at the end of its suction stroke and at the beginning of its discharge stroke.

A pump plunger 1 reciprocates in a cylinder 2 mounted in a housing 3. At its inner end, beyond an annular groove 4, the plunger has edges 5, 6 and a duct 7 which limit the surface of plunger contacting the bore of cylinder 2. Between cylinder 2 and housing 3 there are provided annular chambers or reservoirs 8, 9 communicating by means of openings 10. A port 11 connects the reservoir 9 with the bore of the cylinder or pumping chamber 40. A duct 12 serves for the supply of fuel to the reservoir 9 from a chamber 14 formed in the housing 34 fixed by screws 65 to housing 3. Fuel at relatively low pressure reaches the chamber 14 through the low pressure line 15.

Around the upper end of cylinder 2 a pinion 16 is provided, extending upwardly to form a boss 17 in which the hexagonal portion 18 of the plunger is splined, so that it may be turned by the pinion while it is capable of axial displacement therein. The pinion 16 may be angularly turned for adjustment of the duration of the injection by a rack 19 slidably mounted in a groove 20 formed in the housing 3. One end of the rack 19 is connected with a pressure responsive device, such for example as a piston or plunger slideable in a cylinder or, as shown in the drawings, the movable wall of a bellows 21 mounted in the chamber 14 and surrounded by the fuel supplied through the low pressure line 15. A spring 22 may be provided inside the bellows 21 to balance it against collapse.

Beyond the pinion 16 a washer 23 provides a seat for a spring 24. The outer end of the plunger is formed with a head 25 and a seating collar 26 for the spring 24, and is enclosed by a cover 27 which reciprocates in the pocket 28 of the housing 3 under the influence of any suitable driving means such as the rocking lever 29 shown in Fig. 7, for the pressure stroke of the plunger, the spring 24 effecting the return or suction stroke of the plunger. A small screw 55 through the housing 3 engages a slot 56 in the cover 27 retaining the cover over the plunger and its spring but permitting its reciprocating movement.

Between the cylinder 2 and the cap 30 which screws into the housing 3, a valve seat piece 31 and an intermediate piece 32 are provided, tightly clamped together and against the cylinder 2 when the cap 30 is screwed. A gasket 33 of ductile or resilient material prevents leakage of fuel between the housing 3 and the cap 30, and between the cap 30 and the valve seat piece 31. Ducts 34, 35 through the pieces 32 and 31 lead the fuel from the pumping chamber 40 to a chamber 41 in the piece 31. In this chamber 41 is a seating for an injection valve 42 which has an area formed by a shoulder 43 whereby it is lifted by the pressure of the fuel in the chamber 41 to permit the flow of fuel to suitable spray holes 44. The lifting of the valve 42 is resisted by a spring 46 in the chamber 47 whose load determines the minimum injection pressure. A drain hole 48 may be provided in order to maintain in the chamber 47 the same pressure as in the annular chamber 50 which latter, through holes 52, communicates with the reservoir 9.

The complete assembly constitutes a unit fuel pump and injection nozzle which may be mounted in a suitable bore 58 through the cylinder head of an internal combustion engine. A gasket 60 is provided to prevent gas leakage from the combustion chamber, and against said gasket 60 the unit is held by two studs 62 (Fig. 2). In operation, fuel at variable and adjustable pressure is supplied through the low pressure line 15 to the chamber 14 where it surrounds the bellows 21 whose interior communicates with the surrounding pressure through the clearance between rod 19 and slot 20. Through the duct 12 the fuel fills the reservoir 9. In the position shown in the drawings the plunger 1 is at the end of its suction stroke and has uncovered the port 11 allowing fuel to flow into the pumping space 40. As the plunger descends, the edge 6 covers the port 11. The pressure rises rapidly in the pumping space 40 and in the chamber 41 containing the spring loaded valve 42 until the pressure is sufficient to lift the valve off its seat, and the fuel is injected into the engine cylinder through the

spray holes 44. The injection continues until the edge 6 uncovers the port 11 which now functions as a pressure relief port through which the remaining fuel displaced by the plunger is bypassed into the reservoir 9.

Air or gas separating out from the fuel in the reservoir 9 fills the chamber 8, and excess air or gas may flow back through the duct 12 to the bellows chamber 14. The air cushion chamber 8 reduces the periodic pressure surges in reservoir 9 and in chamber 14 which surges accompany the opening and closing of the port 11. In operation, pressure variations in the bellows chamber 14 obtained by changing the pressure of the fuel in the low pressure line 15 in a manner to be later described, result in contraction or expansion of the bellows 21, in axial displacement of the rack 19 and rotation of plunger 1, whereby, owing to the helical edges 5 and 6 controlling the port 11, the volume of fuel injected by the pump unit may be controlled.

Excess of air or gas can be eliminated from the reservoir 9 of the pump shown in Fig. 1 through the duct 12 only when the axis of the pump is substantially vertical, the spray nozzle discharging downwardly, or when the axis of the pump is horizontal and the duct 12 emerging from the uppermost part of the reservoir 9, or for positions of the pump intermediate between the two positions described. In the pump unit shown in Fig. 3 the air and gas bubbles in excess of the amount necessary for air cushioning can be eliminated from the reservoir 82 whatever the orientation of the unit in the space, relative to the vertical line, may be. The circular flanges 71, 72 of the pump cylinder 2, expanding and coming into contact with the bore of the housing 3, have openings 74, 75 through which the reservoir 82, receiving fuel from the duct 12, communicates with the chambers 83 and 84. Annular grooves 76, 77 are provided in the flanges 71 and 72 respectively, which grooves communicate, through radially drilled ducts 78, 79, with ducts 80 communicating with circular grooves 81, 88. The spring chamber 47 communicates through a duct 90 with the groove 87, while the groove 88 communicates through a small chamber 92 and a pipe union 93 with the fuel return pipe 91. That portion of the outer cylindrical surface of the flange 71 which is comprised between the groove 76 and the chamber 83 fits tightly into the bore of the housing 3 and prevents any direct leakage between the chamber 83 and the groove 76, while the cylindrical surface between the groove 76 and the reservoir 82 fits loosely in said bore. Similarly, flange 72 fits tightly into the bore of housing 3 between the chamber 84 and the groove 77, while it fits loosely between this groove and the reservoir 82. Since, as it will be seen later, the fuel pressure in the return pipe 91 is lower than in the reservoir 82, a steady flow will be maintained from the reservoir 82 to the grooves 76 and 77 and from these grooves to the return pipe 91. Owing to the fact that the total orifice area between the reservoir 82 and the grooves 76 and 77 is considerably smaller than the area of the ducts connecting said grooves with the pipe 91, the pressure in the grooves 76 and 77 will be substantially the same as in the return pipe 91. All the undesired air or gas can thus be eliminated from the reservoir 82, while only a comparatively small amount of liquid fuel can escape. Whatever position, relative to the vertical line, the pump unit may assume, air or gas cannot be entirely eliminated from at least one of the cushion

chambers 83, 84, while excess air or gas from the actual top of the reservoir 82 will be drawn into the return pipe 91, thereby reducing the risk of bubbles being introduced through the port 11 in the pumping space 40.

The above mentioned steady flow of fuel from the reservoir 82 through grooves 76 and 77 to the return pipe 91 further serves to cool the pump.

An air cushioning chamber 92 may be provided between the groove 88 and the return pipe 91. Since the pipe union connecting the pipe 91 with the housing 3 projects with its free end 93 toward the center of chamber 92, here too, whatever the orientation of the pump may be, some air or gas will always be contained, in order to reduce the periodic fluctuations of the pressure in the return pipe 91.

Air or gas may separate from liquid fuel in the pumping chamber 40 where it might interfere with the correct operation of the pump. Means for venting said chamber are shown in Fig. 5. An annular groove 96 is provided in the plunger 1. Between the grooves 96 and 4 the diameter of the plunger is such that a certain clearance 98, larger than in other portions of the plunger, is left between the plunger and the cylinder bore. A duct 97 is drilled through the cylinder 2 connecting the groove 88 with that portion of the cylinder bore which is contiguous with the groove 96 when the plunger is at the top end after its suction stroke and before its discharge stroke during the "dwell" period provided by the "dwell" portion of the cam. During this period the port 11 is open and the fuel pressure in the pumping chamber 40 equals the pressure of the low pressure line, while, owing to the fact that the area of the ducts between the groove 96 and the pipe 91 is considerably larger than that of the aperture 98, the pressure in the groove 96 is substantially the same as in the return pipe 91. An upward scavenging flow, whose volume increases with an increase of pressure in the low pressure fuel line, will therefore be established during the "dwell" period, from the port 11 to the groove 4 and, through the aperture 98, to the return pipe 91, and the air or gas bubbles, tending to flow upwardly in groove 4, are eliminated from the pump. Obviously the unit as shown in Fig. 5 is designed to operate with its axis substantially vertical, the nozzle discharging downwardly.

A further modification is shown in Fig. 6, designed to assure venting of the pumping chamber 40 whatever the orientation of the pump unit in the space, relative to the vertical line, may be. In addition to the groove 87 shown in Fig. 3, a second concentric groove 99 is provided in the lower terminal face of the cylinder 2. An annular clearance space 100 establishes between the pumping chamber 40 and the groove 99 an aperture of area about equal to that of aperture 98. A duct 101 connects the groove 99 with that portion of the cylinder bore which is contiguous with the groove 88 when the plunger assumes its top outer end position, whereby, during the "dwell" period between the end of the suction stroke and the beginning of the discharge stroke of the plunger, the groove 99 is also maintained substantially at the pressure of the return pipe 91, and an additional scavenging flow from the port 11 to the groove 99 will be established. A cavity 105 having its end connected with the groove 4 through several drills 106 is provided at the inner end of the plunger 1. According to the orientation of the pump relative to the vertical line, the air or gas bubbles,

tending to flow upwardly, will be eliminated through the aperture 98, or 100, or both. Bubbles from the cavity 105 will also flow either to the groove 4 through the drills 106, or to the pumping chamber 40, or both, and will be eliminated therefrom. To reduce the danger that bubbles be drawn into the duct 34 leading to the nozzle 41, the duct 34, drilled in a central extension 103 of the intermediate piece 32, has its inlet opening about in the center of the pumping chamber 40.

In the above disclosed example of embodiment of the invention engine fuel is employed as the fluid medium serving to actuate the pressure responsive bellows 21. It is however to be clearly understood that according to the present invention any other suitable fluid, for instance lubricating oil, may be used as medium for actuating the bellows 21 to control the fuel delivery.

While the pump units above described may be actuated by any suitable reciprocating mechanism, a preferred embodiment is shown in Fig. 7, wherein the timing adjustment is controlled by hydraulic means. In the pump unit a stop member 120 having a cylindrical portion adapted to slide axially on the boss 17 of the pinion 16 is provided to limit the outward displacement of the plunger 1. The lower portion of the member 120 is externally threaded to engage a companion helical thread formed in the bore of pinion 125. A thrust washer 126 solidly fastened to the housing 3 by screws 127, serves as a seat for the spring 24 and prevents pinions 125 and 16 from axial displacement. The end of one at least of the screws 127 extends into an axial groove 128 of the stop member 120 to prevent it from rotating. Annular displacement of pinion 125 will therefore displace axially the stop member 120 and thereby alter the outer position that the plunger 1, urged outwardly by the spring 24, may assume. Various means, obviously, may be provided to rotate the pinion. In the preferred embodiment illustrated in Fig. 7, rotation of the pinion 125 is controlled, in a way similar to that already described in detail for the pinion 16, by a rack formed in a rod 130 connected with the movable wall of a bellows 131 balanced against collapse by an inner spring 132 and contained in a housing 133 fixed by small screws to the housing 3. A duct 135, extending to the center of the chamber 92 communicating with the groove 88, leads the fuel and the air and gas bubbles eliminated from the pump to the space comprised between the housing 133 and the bellows 131. The pipe 136 is the return line. Axial adjustment of the stop member 120 can thus be obtained by varying the pressure in the fuel return pipe.

A rocker lever 29 actuating the plunger 1 is operated, through a rod 110 and a lifter 111 capable of reciprocating inside the guide 112, by a cam 113 carried by the engine camshaft. Oil under pressure from the lubricating system of the engine is supplied through a conduit 115 to an oil chamber 116 and, through a duct 117, to a piston chamber 118. A check valve 119 prevents the oil in chamber 118 from returning to chamber 116. When the lifter 111 rests on the base circle or "dwell" portion of the cam 113, and the pump plunger is maintained by the spring 24 in its outer top position against the stop member 120, the piston spring 121 lifts the piston 122, the intermediate piece 123 and the push rod 110 so that all clearances between rod 110, rocking lever 29, cover 27 and plunger 1 disappear. As the piston 122 moves outwardly, increasing the volume of the piston chamber 118, the check valve 119 moves off

its seat and the chamber 118 is filled with oil from the chamber 116. As the camshaft rotates, after the "dwell" period the cam 113 pushes the lifter body 111 upwardly, tending to decrease the volume of chamber 118 and forcing the valve 119 onto its seat, whereupon further rotation of the camshaft lifts the piston 122 and operates the fuel pump. So long as the plunger 1 is out of contact with the stop member 120, the load is carried by this column of oil in the chamber 118. During this period a predetermined slight leakage of oil occurs, so that the volume of chamber 118 is reduced, and space is provided for a new amount of oil to fill the chamber 118 and thus maintain the adjustment during the next cycle, as soon as the plunger 1 contacts the stop member 120 again. The hydraulic lifter above described is well known in the art, particularly in connection with valve lifting mechanisms of internal combustion engines. Any other suitable type of hydraulic or mechanical slack adjusting device may obviously be substituted therefor.

For a given angular adjustment of plunger 1 relative to the cylinder 2, and for a given cam profile, the beginning of the effective delivery stroke of plunger 1 depends on the distance between the outermost position of plunger 1, as determined by the stop member 120, and the position of the same plunger 1 in which the port 11 is being covered by the plunger. Variation of the beginning of the injection may therefore be obtained by axially displacing the stop member 120 relative to cylinder 2 and in turn by changing the fuel pressure in the return pipe 136.

Obviously, mechanical instead of hydraulically actuated devices may be employed for altering the axial adjustment of the stop member 120 to vary the injection timing. In particular, if in the above described mechanism the stop member 120 has a fixed position relative to the cylinder 2, the hydraulic lifting device instead of being axially adjustable will automatically maintain a constant timing adjustment of the pump discharge, independently of thermic dilatation of different parts, changes in the thickness of the gasket 60 and so forth.

An arrangement of fuel supply system for internal combustion engine according to the invention is diagrammatically shown in Fig. 8, in which a fuel transfer pump 140, shown as a gear pump driven through an extension 141 of the engine camshaft, draws fuel from a tank, not shown in the drawing, through a suction pipe 142 containing a non-return valve 143 to prevent the fuel system from emptying when the engine is stopped, and delivers fuel under pressure to the pipes 137 and 15 and to the bellows housing 64 of pump 3. The volume of fuel delivered by the transfer pump 140 is considerably in excess of the maximum volume of fuel that can flow through the pump or pump 3 whereby, despite the action of the air cushioning chambers which may be included in the low pressure system, the pressure of fuel therein can rapidly be changed by a relief or pressure regulating valve 145 comprising a slidably mounted valve plunger 146 loaded by a spring 147, and a return pipe 148 leading to the fuel tank or to the suction pipe 142. Obviously, the fuel pressure in the low pressure system and in the bellows housing 64 is controlled by the load of the spring 147. A control lever 150 is provided to adjust the load of the spring 147 and thereby to control the quantity of fuel supplied by the pump 3.

The housing 133 of the pump 3 containing the

bellows for the timing adjustment is connected through pipes 134 and 136 to a relief or pressure regulating valve 151 similar to valve 145 and including a valve plunger loaded by a spring 152 whose load can be adjusted by a control lever 153, and a return pipe 154 leading, as the pipe 148, to the fuel tank or to the suction pipe 142. Fuel pressure in the pipes 134, 136 and in the bellows housing 133 and in turn the timing adjustment of the periodic discharge of the pump unit 3 can therefore be controlled by the lever 153.

In order to avoid that pressure changes in the bellows housings 64 and 133 interfere with the correct scavenging and venting of the pump 3, design and operation of the relief valves 145 and 151 shall be such that the fuel pressure will always be substantially higher in the housing 64 connected with the low pressure line than in the housing 133 connected with the return pipe.

Speed responsive means for operating the relief valves 145 and 151 are shown in Fig. 9. From that extension of the engine camshaft 141 driving the transfer pump 140, a pair of gears drive a vertical shaft 158 on which is arranged a governor having flyballs 157 acting on an axially slidable sleeve 158 connected with one end of a lever 163, the other end of which controls, through the spring 147, the relief valve 145. Through a sleeve 160 and a thrust bearing 161, the load of the governor spring 159 may be adjusted by a control lever 162. For a fixed position of said lever, the governor 157 will maintain the engine at a corresponding substantially constant speed. Said speed will however increase or decrease with a decrease or increase in the engine load, respectively. In fact the governor must regulate the speed of its engine in such manner that the speed is lower for full load than for no load. In one of the preferred embodiments of the invention, shown as an example in Fig. 9, the engine speed is such that the corresponding centrifugal force applied to the flyballs 157 balances the resilient load exerted on sleeve 158 by the spring 159 minus the hydraulic load applied by the fuel pressure to the upper surface of valve plunger 146 and transmitted through lever 163 to said sleeve 158. For a given adjustment of the control lever 162 a decrease of engine load causes an increase of engine speed and, through the action of flyballs 157, an upward displacement of sleeve 158 and a downward displacement of valve plunger 146, whereby the fuel pressure in the low pressure system and the engine fuel supply are reduced. The hydraulic load applied to the upper end of valve plunger 146 and transmitted to sleeve 158 against the load of spring 159 is thus decreased, and a higher value of the centrifugal force transmitted by the flyballs 157 to said sleeve 158 is required to maintain the latter in equilibrium. The engine speed will therefore assume a higher value. Conversely, an increase of engine load causes a decrease of engine speed, a downward movement of sleeve 158 and an upward movement of the valve plunger 146 determining an increase of fuel pressure in the low pressure system and an increase of engine fuel supply. The hydraulic load exerted on valve plunger 146 and transmitted to the sleeve 158 against the load of spring 159 increases, whereby the centrifugal load required for maintaining said sleeve in equilibrium is reduced, and the engine speed assumes an accordingly lower value. The speed at which the governor maintains the engine is dependent upon the compression load of the spring 159 and thereby upon the angular adjustment of the speed

control lever 162. On the same vertical shaft 158 a second governor is arranged, having flyballs 157, a governor spring 156 and a sleeve 155 connected with one end of a lever 163, the other free end of which controls the valve spring 152 of the relief valve 151 and thereby the pressure in pipes 138 and 134 and in the bellows housing 133. The timing of the periodic discharge of the pump unit will therefore vary automatically with the engine speed. Since both the governors 157 and 158 have to control only a relief valve, their energy can be very small.

The stabilizing and compensating effect obtained by the application of an axial variable fluid pressure load to the slideable valve 146 of the governor 157 shown in Fig. 9 may more clearly and distinctly be described as follows: As the engine operates under steady load and speed, the valve 146 remains in a corresponding definite axial adjustment. Neglecting the weight of valve 146, the three forces applied thereto by the flyballs 157, by the spring 159 and by the fluid pressure exerted on the upper end thereof are in equilibrium. If the engine load decreases the engine accelerates and the increased centrifugal force of the flyballs 157 causes a downward movement of the valve 146 thus determining a pressure drop in the pressure lines 137 and 15 and initiating a movement of the resiliently loaded bellows 21 connected with the control racks 19 in a direction to decrease the engine fuel supply and in turn the speed thereof. As a result the axial fluid pressure load exerted on the upper end of the valve 146 decreases and restrains the downward movement thereof. Although this restraining action due to the variation of the fluid pressure exerted on the valve 146 is very small as compared to the centrifugal force of the flyballs 157 and to the load of spring 159, it prevents overtravel of the valve 146 and causes the latter to resume its correct adjustment quickly so that an underspeed condition of the engine does not occur and the danger of hunting is avoided.

Conversely when the engine load is increased the engine decelerates and the action of the governor is the reverse of that just described. The valve 146 is then displaced upwardly by the spring 159 acting against the decreasing centrifugal force of the flyballs 157. This reduces the effective opening of the discharge valve 145 and causes pressure increase in lines 15 and chambers 14 to initiate displacement of the bellows 21 in a direction to increase the engine fuel supply and the engine speed. The axial fluid pressure exerted on the valve 146 increases so as to restrain the upward movement thereof initiated by the change of centrifugal force, thus avoiding overtravel of the valve 146 and overcorrection on the part of the bellows 21.

In the example of embodiment of the invention which is illustrated in Fig. 9 the flyballs 157 are connected with the valve 146 by means of a lever 163 and a spring 147. As stated above the axial fluid pressure exerted on valve 146 is very small as compared to the centrifugal force transmitted by the flyballs 157 to the sleeve 158, and accordingly the load on spring 147 is very small as compared to that of spring 159. Obviously the rate of deflection of the connecting spring 147 may be so determined as to suit the desired requirements, and where no appreciable amount of elasticity is desired between lever 163 and valve 146, the spring 147 may be designed sufficiently stiff so that the deflections thereof under the small loads to which

it is subject are negligible, this spring thus merely performing the function of a connecting element.

While in Figures 8 and 9 one pump unit only is shown, inserted between the pipes 137 and 134, it is obvious that such pipes may extend parallelly, and between them several pumps may be inserted, as shown diagrammatically in Fig. 10.

These embodiments of the invention have been shown merely for purpose of illustration and not as a limitation of the scope of the invention. It is, therefore, to be expressly understood that the invention is not limited to the specific embodiments shown, but may be used in various other ways, in connection with other mechanisms and regulators, and various modifications may be made to suit different requirements, and that other changes, modifications, substitutions, additions and omissions may be made in the construction, arrangement and manner of operation of the parts without departing from the limits or scope of the invention as defined in the following claims.

In interpreting the claims, where they are directed to less than all of the elements of the complete system disclosed, they are intended to cover possible uses of the recited elements in installations which may lack the non-recited elements.

Certain features herein disclosed are claimed in my copending applications Serial No. 254,355 filed February 3, 1939, Serial No. 333,529 filed May 6, 1940, Serial No. 376,170 filed January 27, 1941, and Serial No. 466,041 filed November 18, 1942.

What I claim is:

1. In combination, a fuel pump to intermittently deliver fuel to an internal combustion engine, said pump including a cylinder having port means and a plunger having a reciprocating motion of constant stroke in said cylinder and adapted to cover and uncover said port means, a fuel conduit connected with said pump, a mechanism whereby the mean axial position of said plunger relative to said cylinder and thereby the timing of the intermittent fuel delivery of said pump may be varied, means responsive to the fuel pressure in said conduit and operatively connected with said mechanism, and means for adjusting the fuel pressure in said conduit to control the timing of said intermittent fuel delivery.

2. A fuel pump for intermittently delivering fuel to an internal combustion engine, said pump including fuel inlet means, a reservoir connected with said inlet means, fuel return means, venting means connecting said inlet and said return means whereby said reservoir is scavenged and cooled by a continuous flow of fuel determined by the difference of pressure between said inlet and said return means, a control mechanism for varying the fuel delivery of said pump, and means responsive to the fuel pressure in said inlet means and operatively connected with said mechanism whereby an increase or decrease of the fuel pressure in said inlet means determines an increase or decrease respectively of both the fuel delivery of said pump and flow of fuel scavenging and cooling said reservoir.

3. A fuel pump for intermittently delivering fuel to an internal combustion engine, said pump including a cylinder having port means, a plunger reciprocable in said cylinder and adapted to cover and uncover said port means, fuel inlet means, fuel return means, a pressure chamber in said cylinder at one end of said plunger, venting means controlled by said plunger for intermittently connecting said chamber with said inlet and said return means whereby said chamber is scavenged by an intermittent flow of fuel deter-

mined by the difference of pressure between said inlet and said return means, a control mechanism for adjusting the fuel delivery of said pump, and means responsive to the fuel pressure in said inlet means and operatively connected with said mechanism whereby an increase or decrease of the fuel pressure in said inlet means causes an increase or decrease respectively of both the fuel delivery of said pump and the flow of fuel intermittently scavenging said chamber.

4. A fuel pump as defined in claim 2 said pump including a cylinder having a port in said reservoir, said venting means including orifices connecting said reservoir with said fuel return means, said orifices surrounding said port whereby at whatever angle said pump may be set relative to the vertical line fuel including any air, gas or vapor bubbles may be vented from said reservoir at a point higher than said port.

5. A fuel pump as defined in claim 3, including an outlet duct for the fuel discharged under pressure from said chamber, the inner end of said duct extending toward the center of said chamber, said venting means including orifices connecting said chamber with said return means, said orifices surrounding said inner end of said duct whereby at whatever angle said pump may be set relative to the vertical line fuel including any air, gas or vapor bubbles may be intermittently vented from said pressure chamber at a point higher than said inner end of said duct.

6. A fuel injection system for internal combustion engines including interchangeable pumps for intermittently discharging fuel under pressure to said engine, conduit means connected with said pumps for supplying the latter with fuel, hydraulically operated control means included in each of said pumps whereby the fuel discharge of each of said pumps is individually controlled by the pressure of said fuel supplied thereto through said conduit means, a fuel transfer pump for delivering fuel under pressure to said conduit means, and valve means for controlling the fuel pressure in said conduit means and thereby controlling the engine fuel supply.

7. A fuel injection system as defined in claim 6 in which said valve means are actuated by governing means.

8. In combination with a fuel injection system including pumps for intermittently delivering fuel under pressure to an internal combustion engine and conduit means connected with a source of fuel under pressure and with said pumps for supplying the latter with fuel, means whereby the fuel delivery of said pumps is controlled by the pressure of said fuel supplied to said pumps and decreases or increases with a decrease or increase of the pressure of said fuel respectively, and valve means for regulating the pressure of the fuel supplied to said pumps, the adjustment of said valve means being determined by the loads transmitted thereto by resilient means tending to increase the fuel pressure in said conduit means, by means responsive to the speed of said engine and acting against said resilient means, and by a compensating load applied to said valve means by fuel having substantially the same pressure as in said conduit means and acting in opposition to said resilient means, whereby the speed of said engine is higher at no engine load than at full engine load.

9. In combination with a fuel injection system including pumps for delivering fuel under pressure to an internal combustion engine, a source of liquid under pressure, conduit means connected with said source and said pumps, means whereby the

fuel delivery per cycle of said pumps is controlled by the pressure of said liquid and increases or decreases with an increase or decrease of said pressure respectively, and valve means for regulating the pressure of said liquid to control the fuel delivery of said pumps, the adjustment of said valve means being determined by the loads transmitted thereto by resilient means under the control of the operator, by means responsive to the speed of said engine and acting against said resilient means, and by the pressure of said liquid acting against said resilient means, whereby the speed of said engine increases or decreases with a decrease or an increase of the load of said engine respectively.

10. A fuel metering pump for intermittently delivering fuel to an internal combustion engine, said pump including a cylinder and a plunger having a reciprocating motion of constant stroke in said cylinder, means for controlling the fuel delivery per cycle of said pump by angularly adjusting said plunger and means for varying the timing of said delivery by changing the mean axial position of said plunger relative to said cylinder, duct means for the fuel inlet, conduit means for the outlet of excess fuel, a fuel flow communication including small aperture means between said duct means and said conduit means whereby the fuel pressure in said duct means and in said conduit means may have different values, pressure responsive means actuating said first mentioned means whereby the fuel delivery of said pump is determined by the fuel pressure in said duct means, and pressure responsive means connected with said second mentioned means whereby the timing of said fuel delivery is dependent on the fuel pressure in said conduit means.

11. In a fuel pump for intermittently delivering fuel to an internal combustion engine, a plunger having a reciprocating motion of constant stroke, means for controlling the fuel delivery by a turning adjustment of said plunger and means for varying the timing of said delivery by changing the mean axial position of said plunger in said pump, first and second conduit means for a liquid medium, pressure responsive means connected with said first mentioned means whereby the fuel delivery of said pump is determined by the pressure in said first conduit means, and pressure responsive means connected with said second mentioned means whereby the timing of said delivery is dependent on the pressure in said second conduit means.

12. A fuel injection system for a multicylinder internal combustion engine including fuel pumps as set forth in claim 11, first and second duct means connected with said first and second conduit means of said pumps respectively, valve means for regulating the pressure in said first conduit means to control the fuel delivery of said pumps, and valve means for regulating the pressure in said second conduit means to adjust the timing of the fuel delivery of said pumps.

13. A fuel injection system for internal combustion engine including in combination a pump having a cylinder, port means in said cylinder, a plunger having a reciprocating motion in said cylinder and controlling said port means, tappet means for actuating said plunger from an engine driven cam to effect the discharge stroke of said plunger, resilient means for causing the suction stroke of said plunger, adjustable stop means for determining the axial position of said plunger at the end of said suction stroke, means for varying the adjustment of said stop means, and means

for automatically adjusting the length of said tappet means in dependence of the adjustment of said stop means.

14. In a fuel injection system for multicylinder internal combustion engine including fuel metering units, a source of liquid under pressure, conduit means connected with said source and with said units; means in said units for controlling the fuel delivery thereof; resilient means and diaphragm means in said units operatively connected with said means thereof for varying the fuel delivery of said units in response to changes of pressure of said liquid; and pressure regulating means for adjusting the pressure of said liquid to control the fuel delivery of said units.

15. In a fuel supply system for multicylinder internal combustion engine, including fuel metering units, a source of fuel and conduit means connected with said source and said units; means in said units for controlling the fuel delivery thereof; resilient means and diaphragm means in said units operatively connected with said means thereof for varying the fuel delivery of said units in response to changes of pressure of said fuel; and pressure regulating means for adjusting the pressure of said fuel to control the fuel delivery of said units.

16. An engine fuel injection pump including means for varying the fuel discharge thereof, fuel containing means, and fuel pressure actuated means operatively connected with said first mentioned means for increasing or decreasing the fuel discharge of said pump upon increase or decrease respectively of the fuel pressure in said containing means.

17. An engine fuel injection system including, in combination with a source of fluid under pressure, fuel injection pumps having fluid containing means, conduit means connected with said source and said containing means of said pumps, fluid pressure actuated delivery control means in said pumps for increasing or decreasing the fuel delivery of said pumps upon an increase or decrease respectively of the fluid pressure in said containing means, and means for regulating the fluid pressure in said containing means.

18. An engine fuel injection system including a pump having a cylinder, port means in said cylinder, a plunger in said cylinder controlling said port means, tappet means for actuating said plunger from an engine driven cam to effect the discharge stroke of said plunger, resilient means

for causing the suction stroke of said plunger, stop means in said pump for determining the position of said plunger at the end of said suction stroke, and means for automatically adjusting said tappet means to render said stop means effective and eliminate backlash.

19. An engine fuel injection system including a pump having a cylinder, port means in said cylinder, a plunger in said cylinder controlling said port means, cam and tappet means for effecting the discharge stroke of said plunger, resilient means for causing the return stroke thereof, means in said pump for determining the end of said return stroke, and hydraulic means for automatically adjusting the effective length of said tappet means.

20. An engine fuel injection system including, in combination with a fluid pump, fuel injection pumps, conduit means for connecting said injection pumps with said fluid pump, fluid pressure actuated means in said injection pumps for varying the fuel discharge thereof with changes of fluid pressure in said conduit means, and valve means for regulating the fluid pressure in said conduit means.

21. In combination, an engine fuel injection pump having a cylinder, port means in said cylinder, a plunger in said cylinder controlling said port means, tappet means to effect the discharge stroke of said plunger from an engine driven cam, resilient means for causing the suction stroke of said plunger, adjustable means for determining the end of said suction stroke, hydraulically actuated means for varying the adjustment of said adjustable means to change the injection timing of said pump, and means for the automatic adjustment of said tappet means.

22. An engine fuel injection system including separately mounted fuel injection pumps, each of said pumps having fuel delivery control means, fluid containing means and fluid pressure responsive means operatively connected with said control means for varying the fuel delivery of said pumps as a predetermined function of the fluid pressure in said containing means, conduit means for interconnecting said containing means of said pumps whereby the fluid pressure in the latter means is maintained uniform, and means for regulating the pressure in said fluid containing means.

FERDINANDO CARLO REGGIO.
